GRILLE

Loyd E. Heasley and Nelson E. Cole, Holland,
Mich., assignors to Hart & Cooley Manufacturing Company, Holland, Mich., a corporation of
Delaware

Application August 1, 1938, Serial No. 222,435

7 Claims. (Cl. 98—106)

This invention is concerned with a register for directing the passage of air into a room from a flue which carries the air, and through which it is moved either by natural movement or by forced circulation thereof.

Registers of this character are usually placed in the wall of the room and while the more modern practice is to locate such registers toward the ceiling of the room, they may be located at other positions. The air which passes through the flue and thence through the register into a room is heated during the colder months of the year and may be cooled during the warmer months, the term applied to the tempering of the air being that it is "conditioned," and a room into which the air is directed is "air conditioned" in accordance with the different temperatures at different seasons of the year.

It is undesirable that heated air should be directed upwardly into the room and toward the ceiling, particularly when the register is located adjacent the ceiling. On the other hand, it is undesirable that colder air coming into the room should be directed downwardly by the register. Heated air naturally rises because of its lighter specific gravity and colder air will descend for the same reason.

The present invention is concerned with a register of novel construction wherein the air may be directed horizontally through the register into the room, or by small change and adjustment of parts may have its angle of direction changed either slightly above the horizontal or slightly below, the usual maximum limits both above and below the horizontal not exceeding 15°. The register is also provided with structure whereby it may be completely closed so that no air will pass from the flue into the room. The construction for attaining these advantages and results is one which is simple and comparatively inexpensive to make, readily assembled, and the completed register is easily installed.

The invention may be understood from the following description taken in connection with the accompanying drawing, in which:

Fig. 1 is a front elevation of a register made in accordance with our invention, some of the grille bars being broken away for clearness of disclosure.

Fig. 2 is a partial end elevation and partial vertical section showing the register in closed position, and

Fig. 3 is a vertical section showing the register in open position and in its association with an air-carrying flue.

Like reference characters refer to like parts in the several figures of the drawing.

In the register structure a frame usually of rectangular shape is provided and as disclosed, the sides and ends of the register are pressed or formed from sheet metal with vertical face flanges 1 and inwardly extending flanges 2 at right angles thereto. Around the flanges 2 a second frame 3 is provided of Z-bar material which is secured in place by spot welding or other suitable means. A plurality of vertical grille bars 4 extend between the upper and lower horizontal flanges 2 and at their ends may be pivotally mounted on pintles and joined together in groups by a connection to the several plates 5 lying against the upper side of the lower inwardly extending flange 2, and which are held by screws 6 and leaf springs interposed between the heads of the screws and the under sides of the lower flange 2, the screws passing through slots in said flange 2 whereby a group of the bars may be tilted to one side or the other of a central vertical plane. However, this specific form of structure and of the adjustment of the grille bars is in no sense essential to our invention and the bars may be, and oftentimes in practice are, secured at their ends without providing any means for adjustment thereof as described. The specific structure of the frame and grille bars as outlined is not to be considered as limiting the invention thereto in any respect, as the invention is applicable to many other specific forms of frame structure and vertical or other type of grille bars.

The register is adapted to be installed at an opening in the wall 7 of the room and form an outlet for air passing upwardly through an air-carrying flue 8 which, in some instances, is closed at its upper end immediately above the register and in others may be continued upwardly to an upper room in the building. In any case, air moves upwardly through the flue either through natural force or because of being blown or forced and will pass outwardly through the register when the same is open to permit such passage.

With our invention a sheet metal plate 9 is permanently secured by welding or other permanent connection to a depending leaf 10 of a hinge which extends substantially the full length of the register, said leaf having a hinge connection about hinge pin 11 to a second hinge leaf 12 which, together with a vertical positioned flat bar 13 in front of it, is secured to the upper horizontal member of the frame described, usually by screws as shown. The plate 9 may be

5 moved from a position where it lies against the rear side of the register frame thereby stopping passage of air as in Fig. 2, to a second position, as in Fig. 3 where it extends downwardly and rearwardly from the pivot rod 11, its lower free edge coming substantially to the rear vertical wall of the flue 8.

10 It is also apparent that the plate may occupy intermediate positions between the closing and fully open positions shown.

15 In the structure shown, a member having a vertical leg 14 is permanently secured at one end and at the rear side of the plate 9. A vertical slot 15 is cut in the leg adapted to be traversed by the shank of a bolt or screw 17 carried at the inner end of an operating handle 16. The handle is pivotally mounted between its ends on a pivot pin 18 carried at a side of the surrounding frame 3, and passes through a vertical slot in the face 20 flange 1 at one end of the frame. The handle is accessible for manual operation and by pulling down on the outer free end of the handle the plate 9 may be swung from its closed position in Fig. 2 to the open position in Fig. 3.

25 Vanes 19 shown as two in number, though the number may be increased if necessary, extend lengthwise of and within the frame back of the bars 4 and are carried on flexible tapes 20, the tapes passing through said vanes at spaced-30 apart points. Two of the tapes are shown used one adjacent each end of the register, and each at one end passes through the plate 9 and is provided with a stop at 21 at the rear side of the plate. Also stops 21 are secured to the tape at 35 each side of a vane 19 at each place where the tape passes therethrough. The rear or inner sections of the tape from the plate 9 pass downwardly and forwardly through rear portions of the vanes 19 and around rods 22 located between 40 pairs of the bars 4 near their lower ends, and are then turned back upon themselves, extending upwardly through the front portions of the vanes 19, and at their upper ends are clamped between the plate 13 and the upper leaf 12 of the hinge 45 previously described. The stops 21 for convenience may be sheet metal clips bent around each side of the tape and attached thereto.

50 When the air-deflecting plate 9 is in its closed position, as in Fig. 2, the tapes 20 are slackened and the vanes 19 may occupy a position approaching or toward the vertical being located between the front side of the plate 9 and the rear edges of the vertical grille bars 4. On manually operating the handle 16, the tapes have 55 their slack taken up and are tautened and automatically move the vanes to the position shown in Fig. 3, wherein an upper vane is disposed in a plane back of a lower vane and the forward portions of said vanes are located in substantially horizontal planes. The rear portions of 60 the vanes as shown are curved in a downward direction so that air rising vertically or being forced vertically in the flue 8 coming to said curved portions of the vanes has its direction changed and is directed horizontally outward through the bars 4 by reason of the horizontal 65 positions of the forward portions of the vanes 19.

70 The angular position of the vanes may be altered by changing the positions of the stops 21 at the rear side of the plate 9, also by slightly moving the outer end of the operating handle 16 upwardly from its lowermost dotted line position shown in Fig. 3. The position of the vanes may be changed so that the forward portions thereof will be inclined at a slight angle to the horizon-

tal. The vanes automatically occupy the desired position for directing the air horizontally into the room from a vertical flue through which the air is coming to the vanes when the grille is opened for air passage.

5 The construction described is one which is easily made and assembled and in which a very practical and desired efficient direction of the air through a room into a grille is attained. The invention is capable of embodiment in many 10 other forms of structure and is not to be considered as limited to the structural detail specifically disclosed. The invention is defined in the appended claims and is considered to be comprehensive of all forms of structure coming 15 within the scope of the claims.

We claim:

1. In a register construction, an open register frame, a plate pivotally suspended at its upper edge at the rear of the frame and adapted to 20 close the frame in one position or to be moved rearwardly to open said frame and extend downwardly and to the rear from the frame, manually operable means for moving the plate between its closed and open positions, a plurality of air directing vanes, and flexible means secured at their 25 upper ends to the frame and extending downwardly to adjacent the lower side of the frame and thence upwardly to and through said plate, said vanes being carried by said flexible means 30 in spaced apart relation to each other and each connected to said flexible means at two spaced apart points on the vanes whereby the vanes are automatically moved to a substantially horizontal position upon moving the plate to its register 35 opening position.

2. A construction having the elements in combination defined in claim 1, said vanes at their inner portions having downwardly curved sections, as and for the purposes specified. 40

3. In a construction of the class described, a register including an open register frame, a vertical conduit having an opening in its forward side in which the register is located, said conduit being adapted to carry air vertically therein and thence outwardly through the register, a plate 45 pivotally mounted upon a horizontal axis at its upper edge secured to and at the upper rear portion of said register frame, said plate being movable to a vertical position where it closes the 50 frame and to a downward and rearward position where its lower edge comes adjacent the rear side of said flue, whereby the plate will be interposed in the path of movement of the rising air in the flue, manual means for moving the plate to said 55 positions, a plurality of spaced apart vanes, and flexible means carrying the vanes and connected to said frame and plate whereby the vanes are moved to a substantially horizontal position and located partially in the path of movement of the air rising in the flue when said plate is moved to a downward and rearward position, the upper 60 vanes extending rearwardly farther than the lower vanes, thereby directing the vertically rising air in the flue outwardly in a substantially horizontal direction. 65

4. In a register construction, an open frame, a plate pivotally mounted at its upper edge on a horizontal pivot adapted to be moved to a position to close said register at its rear side or swung rearwardly to open the register frame, flexible tapes secured at their upper ends to the rear upper portion of the register and extending downwardly to adjacent the lower side of the register, means around which said tapes are turned and 70

thence extend upwardly to said plate and connect therewith between the upper and lower edges of the plate, a plurality of vanes located in spaced apart relation and carried by said tapes, those 5 portions of the tapes extending from the upper to the lower portions of the frame having connection to said vanes adjacent their forward edges and those portions extending from the lower portion of the register frame to the plate having 10 connection to the vanes toward their rear edges, and means for manually operating said plate between its closed and open positions.

5. In a structure of the class described, an open register frame, a flat metal plate pivotally connected at its upper edge at the rear upper portion of said register frame, said plate being movable to a vertical position to close the frame or to a downwardly and rearwardly inclined position to open said frame, manually operable means 15 mounted on said frame and connected with said plate and extending forwardly of the frame for moving said plate to either of said positions, spaced apart vanes located in front of the plate at different heights with respect to the register, and 20 flexible means connected with said frame, plate and vanes, operated by the plate when it is moved to open position for swinging said vanes from a substantially vertical to a substantially horizontal position, as and for the purposes specified.

6. In a structure of the class described, an open register frame, a member pivotally mounted on said register frame at the rear thereof and movable from a vertical position wherein it is against the frame, to a position inclined to the vertical, 5 manually operable means mounted on said frame and extending forwardly thereof for moving said member to either of said positions, spaced apart vanes located at different heights with respect to the register, and operative flexible connections 10 between said vanes, pivoted member and manually operable means, whereby said vanes are swung from a substantially vertical to a substantially horizontal position when said member is moved from its vertical to its inclined position. 15

7. In a construction of the class described, an open register frame, a plurality of spaced apart vanes located one over the other within said frame, a damper movably mounted on the frame, flexible means connected through said vanes with 20 said frame and damper for swinging the vanes from a substantially vertical position to a substantially horizontal position when the damper is moved away from the frame, and manually operable means for moving said damper. 25
